M. J. OTNESS,
HAT RETAINER,
APPLICATION FILED JAN. 15, 1917.

1,272,507.

Patented July 16, 1918.

UNITED STATES PATENT OFFICE.

MELVIN J. OTNESS, OF STONY PLAIN, ALBERTA, CANADA.

HAT-RETAINER.

1,272,507.

Specification of Letters Patent. Patented July 16, 1918.

Application filed January 15, 1917. Serial No. 142,528.

To all whom it may concern:

Be it known that I, MELVIN J. OTNESS, a subject of the King of Great Britain, and a resident of Stony Plain, in the Province of Alberta and Dominion of Canada, have invented a certain new and useful Improvement in Hat-Retainers, of which the following is a specification.

My present invention relates to retainers 10 for ladies' hats, whereby they may be effectively held in place, when in use.

The principal objects of my invention are, first, to provide hat retainers which may be permanently secured to the hats in such a 15 manner that frequent puncturing of the hat or trimmings is avoided, thereby enabling the user to maintain the good appearance of the hat for a considerable length of time; second, to provide hat retainers which are 20 safe in that they are adapted for coöperation with the hat without the necessity of passing pointed elements through the crown, to be exposed laterally thereof, and without danger of pointed elements entering 25 the scalp of the wearer; and, third, to provide hat fasteners which may be readily operated to secure the hat to the head of the wearer, or operated to permit of removal 30 of the hat without danger of injuring the scalp, or disarranging the hair.

Other objects of my invention are to provide devices of the character described, which may be readily attached to hats, and which may serve to ornament the same, if 35 desired.

Further objects of my invention will appear in the following detailed description, taken in connection with the accompanying drawing, forming a part of this specification, and in which drawings:—

Figure 1 is a perspective view of a hat, in use, equipped with a retainer constructed according to my invention.

Fig. 2 is an enlarged vertical sectional view through a portion of the crown of the hat, showing the fastener applied thereto, parts of the fastener being shown in section to disclose details.

Fig. 3 is a sectional view, looking down on 50 a portion of the crown, the section being longitudinally of a pin forming a part of the retainer.

Fig. 4 is a fragmentary view similar to Fig. 3, showing the pin disposed relative to 55 a guide to facilitate placing or removal of the hat.

Fig. 5 is a view partly in elevation and partly in section, disclosing a portion of a guide for the pin.

In the drawing where similar characters 60 refer to similar parts throughout the views, A designates a hat including a crown B and lining C; D a guide adapted to be secured to the crown B; E a pin carried by guide D; and F a catch for releasably holding 65 pin E rigid with guide D.

Referring first to the guide D, it preferably comprises two elongated arcuate plates 6 and 7, the plate 7 provided with a longitudinally extending rib 8; and, screws 70 9, or other devices for securing the plates 6 and 7 together. While I have herein shown said plates as oval in shape, it is to be understood that they may be formed of other shapes to meet particular conditions or 75 ornamented in order that the plate 6 may add to the esthetic value of the hat. When applying the guide to the hat, the plate 6 may be disposed at the outer face of the crown, while the plate 7 is disposed at the interior 80 of the crown, the devices 9 passing transversely through the body B of the crown, and through lining C, where such is provided, in the example shown, the devices 9 being in screw-threaded engagement with 85 plate 7. In the example shown, each plate is provided with a plurality of transverse ways 10 and 11 the ways of one plate aligned with the ways of the other plate, with their axes diagonally crosswise through said 90 plates. When disposing the guide into operative relation to the hat, the plates 6 and 7 are arranged so that the axes of these ways extend diagonally and upwardly toward the upper portion of the opposite side 95 of the crown, as is clearly indicated by dotted lines in Fig. 1 of the drawing. For a purpose to be subsequently set forth, the ways 11 are relatively larger than the ways 10.

As to the pin E, in the example shown, it 100 comprises a plurality of tines 12, and a plurality of tines 13, and a head 14, joining said tines at adjacent end portions and retaining them in parallel relation one to another. The tines 12 are adapted to extend through the ways or bores 10 of guide D, while the tines 13 are adapted to extend through the ways 11. The tines 12 may be pointed as at 15, and the tines 13 are provided with 110 enlargements 16 at their ends opposite to head 14, the ways 11 being sufficiently

large to permit of passage of enlargements 16 successively through the plates 6 and 7, and through the rib 8 of the last mentioned plate. Thus, the pin E is carried by guide 5 D in a manner to retain it extending diagonally crosswise through the guide. At each way 11, the rib 8 may be provided with a removable member 17, held in place as by a pin 18, said member 17 provided with an 10 extension 19 adapted to constrict its way 11. The projection 19 is so arranged that, when the head 14 is drawn away from the crown of the hat, the enlargements 16 of tines 13 will engage said extension to prevent total 15 separation of the pin from the guide, at which time, the enlargements 16 and pointed end portions 15 of tines 12 are wholly within their respective ways or bores, as is clearly shown in Fig. 4 of the drawing. When the 20 hat is being placed upon the head, the end portions of the tines opposite to head 14, are disposed in their respective ways, after which the head 14 is moved toward the crown of the hat.

25 The catch F is adapted to retain the pin in a fixed position with respect to the guide D, and may consist of a catch proper 19', a stem 20 extending from said catch proper, through one of the tines 12, and a head or 30 button 21 at the end of stem 20. The way 10 through which the said tine 12 carrying the catch F extends, is slightly enlarged so that as the head 14 comes in close proximity to the guide D, the catch proper will 35 pass through the enlargement of way 10 and drop between the plates 6 and 7, as clearly shown in Fig. 2 of the drawing.

When assembling the retainer in operative relation to the hat, the removable members 17 are detached from the rib 8 and again replaced only after the tines have been passed through the alined ways of the plates 6 and 7.

It is to be observed that the retainer may 45 be arranged in operative relation to existing hats without altering the trimming thereof, and that the tines of the pin are so guided that when moved inwardly of the crown,

they assume a position diagonally crosswise of the crown and can not move toward the 50 scalp of the wearer. When it is desired to remove the hat, the user has merely to lift on button 21, and draw the head away from 55 guide D which disposes the end portions of the tines opposite to head 14 in their respective ways, so that the hat may be removed without disarranging the hair.

While I have herein described the device as embodying a plurality of tines, it is to be understood that I do not wish myself limited to such embodiment since retainers may be constructed embodying merely one tine, and changes in details may be made without departing from the spirit or scope of my 60 invention; but

I claim:—

1. In a hat retainer, the combination of a guide including a plurality of plates adapted to be secured to the crown of a hat, said plates each provided with a way, said ways of said plates alined, with their axis diagonally crosswise through said plates, and a pin including a tine slidable in said ways.

2. In a hat retainer, the combination of a guide comprising a body provided with a 75 transverse way, and a removable member adapted to constrict said way; and, a pin including a head and a tine, said tine slidable in said way and provided with an enlargement at its end opposite to said head 80 of a size to pass through said way when the latter is not obstructed, said enlargement adapted to engage the said removable member of said guide to prevent total separation of said pin from said guide.

3. In a hat retainer, the combination of a plurality of plates adapted to be secured to the crown of a hat, in spaced-apart relation, said plates provided with alined transverse ways, a pin carried by said plates including 90 tines extending through said ways, and a catch carried by one of said tines adapted to releasably engage one of said plates between said plates.

MELVIN J. OTNESS.
